INVENTOR.
BERNICE E. HAMILTON

BY
Edward J. Ford
ATTORNEY.

UNITED STATES PATENT OFFICE.

BERNICE E. HAMILTON, OF INDIANAPOLIS, INDIANA.

METAL FIRE BLOCK.

1,412,736.

Specification of Letters Patent. Patented Apr. 11, 1922.

Application filed September 13, 1920. Serial No. 409,990.

To all whom it may concern:

Be it known that I, BERNICE E. HAMILTON, a citizen of the United States, residing at Indianapolis, in the county of Marion and 5 State of Indiana, have invented certain new and useful Improvements in Metal Fire Blocks, of which the following is a specification.

This invention relates to fire blocks and is 10 preferably constructed of sheet metal, the object being to provide a closure for the space between the studding and weather boarding and plastering of a building to prevent the space between these parts acting as a flue or 15 draft opening in case of fire. The prime feature of the invention is in so constructing the fire block that it may be adjusted longitudinally to completely close spaces of varying lengths, it frequently occurring that the 20 studdings are placed at different distances apart.

A further feature of the invention is in providing means for interlocking the adjustable sections together, so that the sections 25 will always remain in a horizontal position, although they may be adjusted lengthwise.

A further feature of the invention is the provision of means for anchoring the fire blocks to the faces of the studding, so that 30 the fire blocks can be quickly and easily applied to use.

Other objects and advantages will be hereinafter more fully set forth and pointed out in the accompanying specification.

35 In the accompanying drawings which are made a part of this application,

Figure 1 is a perspective view showing one of the fire blocks applied to use,

Figure 2 is a top plan view of the fire block, 40 Figure 3 is a transverse sectional view as seen on line 3—3, Figure 2,

Figure 4 is an end elevation of the fire block, and

45 Figure 5 is a top plan view of a slightly modified form of fire block.

Referring to the drawings in which similar reference numerals designate corresponding parts throughout the several views, 1 indicates studding which is of the usual form 50 used in constructing frame buildings, 2 indicates weather boarding, such as is placed on the outside of the studding, and 3 indicates the plastering, such as is placed on the inner face of the studding.

55 It has been the custom heretofore to form fire blocks of wood, such as parts of stud-

ding, or the like, and nail the same between the studding to close the space between the plastering and weather boarding and prevent a draft therethrough; but, in the present instance the fire block 4 is constructed preferably of sheet metal and formed in two sections 5 and 6, the section 5 having a channel 7 extended longitudinally thereof for the reception of a rib 8, which is formed upon 60 and extends longitudinally of the section 6, the channel and rib being so shaped in cross section that they will interlock with each other and hold the two sections of the fire block in proper alignment, and as the channel 70 7 telescopically receives the rib 8 the sections 5 and 6 of the fire block may be adjusted longitudinally to adapt the same for the varying distances between the studding members. The ends 9 and 10 of the sections 75 5 and 6 are bent upwardly at substantially right angles to the fire block proper and fit against the adjacent faces of the studding, any suitable means being provided for securing said ends to the studding, but preferably 80 by forming brads 11 and 12, which brads are preferably so cut from the end sections that they will each present a pointed edge to the studding and may be readily driven into the studding when a blow is delivered against 85 the inner face of the end members. The brads 11 and 12 are formed by making an angular incision in the end members and bending outwardly the severed portions, thereby leaving the brads integral with the 90 end sections at one edge, consequently, when they are driven into the studding they will securely support the fire block in position. The brads 11 and 12 also serve to hold the blocks 4 against any lateral swinging movement.

The channel 7 and rib 8 not only provide means for holding the sections 5 and 6 together, but as they are formed integrally with these sections by bending up parts of the sections, they form a very rigid structure and extend the full length of the sections, so that the ends 9 and 10 will be reinforced.

In Figure 5 is shown a modified form of structure in which the channel and rib are 105 dispensed with and the edges of one of the sections bent over to form channels 13 and in which the end of the other section is mounted, the ends 14 of these sections also having brads 15 struck therefrom for anchoring the 110 fire block to the studding.

This form of device can be very cheaply

manufactured and can be quickly applied to use as it does not require any sawing to fit the same, and but very little effort required to anchor the ends of the fire block to the studding, and as these fire blocks are made in sections they can be extended or contracted to fit between the studding of varying distances apart, and if the space is so small between the studding that the sections when moved to 10 their shortest length are still too long, the ends of the sections may be clipped off so as to shorten the structure.

Having thus fully described my said invention, what I claim as new and desire to 15 secure by Letters Patent, is:

1. A fire block comprising a pair of sections having angularly disposed ends, interlocking reinforcing means on said sections formed by striking up portions of said sections along their longitudinal centers, and means integral with said ends for anchoring the end members in operative position.

2. Means for closing the space between the studding of a building comprising a two-part metallic fire block, a longitudinally extending channel on one section and a co-oper-

ating rib on the other section, said channel and rib being formed by striking up portions of said sections, said channel and rib being substantially triangular shaped in cross sections and interlocking with each other and means for anchoring the outer ends of the sections to the studding.

3. A fire block for building structures comprising a pair of telescoping sections 35 having their outer ends extended at an angle, a longitudinally extending channel on one of said members, a co-operating rib on the other member adapted to enter said channel and telescopically connect the two members, 40 and brads struck from the end portions for anchoring the outer ends of the sections to parts of the building structure.

In witness whereof, I have hereunto set my hand and seal at Indianapolis, Indiana, 45 this 10th day of September, A. D. nineteen hundred and twenty.

BERNICE E. HAMILTON. [L. S.]
